UNITED STATES PATENT OFFICE

GEORGE COOK KIMBALL, OF PITTSBURGH, PENNSYLVANIA

NORMALIZING FURNACE

Application filed March 26, 1930. Serial No. 439,164.

This invention relates broadly to furnaces for heat-treating metal products and is particularly concerned with the normalizing of steel.

The desired end in the normalizing of steel is the production of a uniform or normal sized grain throughout, and consists in heating the material to a point above the upper critical temperature, approximately 1750 or

1800 degrees Fahrenheit and then cooling slowly or rapidly to the lower critical range, approximately 1275 degrees Fahrenheit. It is believed that the quality of the finished product depends a great deal on the size of

15 the grain. For extra deep drawing material going into different sheet stampings, the very fine grain is considered the most desirable.

In drawing, the sharp curves, bends or corners of the small sized grains are comparatively smooth and, according to the opinion of some of those skilled in the art, are much less liable to break than the uniformly large sized grains. The smooth surface afforded by the fine grain material is a very desirable

25 feature, especially when the finished article is to be covered with some thin coating such as the present day automobile finish.

It has been found that the size of the grain depends upon several factors and among these 30 is the time involved in cooling from the upper to the lower critical temperatures. The small grain can be obtained by cooling rapidly whereas prolonged cooling will produce the larger grain sizes, other conditions being the same.

The present method consists in subjecting the material during the normalizing operation to a comparatively rapid cooling action after the upper critical point has been 40 reached, to thereby produce a uniformly small sized grain and a resultant desirably smooth surface product.

An essential object of the present invention, therefore, is the provision of means whereby the material passing through a normalizing furnace may be subjected to a more rapid and better regulated cooling action than has heretofore been possible with furnaces 50 known in the art, to thereby produce a uni-

formly small-sized grain and smooth surface resultant product.

Heretofore normalizing furnaces have been designed by means of which the material passing therethrough may be advanced at varying speeds, and it has also been proposed to remove certain sections of the furnace cover or arch structure, to thereby better control the rate of cooling. By the employment of such methods alone, however, the desired result herein proposed cannot be attained, and moreover, the removal of arch sections permits the furnace gases to escape at points along the furnace which may not prove desirable and yet does not enable the present type of furnace.

In the drawing:

Figure 1 is a view partly in side elevation and partly in longitudinal section of a normalizing furnace embodying the features of the present invention, broken through at various points and moved together to conserve space.

Fig. 2 is a cross sectional view taken on the line 2—2, Fig. 1.

Fig. 3 is a detail view in elevation of a roof section or bung.

Briefly, the furnace as shown is comprised in two main sections, a heating chamber generally designated at A and a cooling chamber in direct alignment therewith and generally designated at B, the metal under treatment being advanced in the direction indicated by the arrow on a succession of 80 suitably driven conveyor disks 5, mounted on transversely-disposed shaft 6, which extend through the side walls 7 of the furnace and are journaled on outside bearing pedestals 8. A fire-door or baffle 9 is provided between the adjoining ends of the two chambers and is adjustable vertically, to control the passage of heat from the heating chamber A to the cooling chamber B.

The floor of the heating chamber is indicated at 10 and the floor of the cooling chamber at 10a. The floor of the heating chamber is formed of refractory material of any desired thickness and this floor as well as part of the floor of the cooling chamber overlies

a layer 11 of insulating material, to reduce dissipation of heat.

The roof of both chambers A and B is made in complementary abutting, removable sections *a* and *b*, which are superimposed upon the side walls 7, a cushion of sand forming a seal at the point where the side walls of the sections rest upon the supporting walls 7. The roof sections of the heating chamber 10 are arched and provided with a heavy lining 12 of refractory material and an outer covering 13 of heat insulating material, in order to withstand the excessively high temperatures to which this part of the furnace is subjected. The sections *b* may be provided with a relatively light lining 12a of refractory material.

As the metal sheets or analogous stock pass from the chamber A into the chamber B, the 20 action of cooling from the upper critical temperature to the lower critical temperature begins and it is with this action that the present invention is concerned.

To obtain a more rapid and better regulated cooling action, an artificially cooled type of top wall or roof section or bung *b*' is provided, the cooling medium being here shown as water. This form of section is shown as built up of metal plate but it will be obvious that other material could be used in place of metal and obtain the same result. Lifting lugs 14 are provided on each section, so that they may be readily moved to various points on the cooling chamber by a crane. It will here be explained that the water-cooled and the non-water-cooled sections are duplicates in size and shape and are interchangeable, whereby many different combinations of water-cooled and non-water-cooled sections may be provided so as to selectively bring about many different cooling conditions in the cooling chamber for the purpose of regulating the cooling conditions in accordance with the character of the metal 45 to be cooled. The top of each section is illustrated as of open construction, but may be closed if desired, and the roof wall 15 is arched. The lower portions of the side walls 16 of the sections are flanged as at 17 where they rest on the side walls 7 of the furnace. The walls of each section provide a chamber or receptacle 18 which is supplied with a cooling fluid, water in the present instance, through a valved inlet pipe 19, the water circulating in the chamber 18 due to thermal action and passing out through an outlet pipe 20. The arched wall 9 may be positioned at varying heights relatively to the metal passing through the furnace, but it is 55 preferred to have the said walls in comparatively close proximity to the metal undergoing treatment, to obtain the full effect of the cooling medium.

In the example illustrated in Fig. 1, a 65 plurality of these artificially-cooled roof

sections are disposed on the end of the cooling chamber B which adjoins the heating chamber A, but said sections may be applied at any point found expedient in view of the grade of metal to be produced.

It will be seen that a predetermined, well-regulated, comparatively rapid rate of cooling may be obtained by the selective application of these artificially cooled sections on the cooling chamber.

What is claimed as new is:

1. A normalizing furnace comprising a heating chamber, a cooling chamber in alignment therewith, means for advancing the metal undergoing treatment through said chambers, said cooling chamber having a roof composed of interchangeable sections superimposed upon the side walls of the chamber, means forming a seal between said roof sections and the side walls of said chamber, some of said roof sections being chambered, means for supplying and circulating a cooling fluid to and through the chambered roof sections, and other of said sections being unchambered and of relatively thin construction to permit radiation of heat to the atmosphere, said roof sections capable of being interchangeably and selectively applied to said cooling chamber to regulate the rate of cooling in said chamber.

2. In a normalizing furnace, a heating chamber, a cooling chamber disposed in communicating relation with the heating chamber, means for selectively establishing and cutting off communication between the chambers, and removable and interchangeable roof sections for the cooling chamber, some of said roof sections being water cooled, whereby the positional disposition of the water cooled roof sections and the other roof sections of the cooling chamber may be selectively changed to bring about the desired cooling effect in the cooling chamber.

In testimony whereof, I have hereunto set my hand.

GEORGE COOK KIMBALL.
